UNITED STATES PATENT OFFICE.

WILLIAM H. DAVIS, OF CROZET, VIRGINIA.

HAMMOCK.

1,181,508.

Specification of Letters Patent.

Patented May 2, 1916.

Application filed March 16, 1915. Serial No. 14,725.

To all whom it may concern:

Be it known that I, WILLIAM H. DAVIS, a citizen of the United States, residing at Crozet, in the county of Albemarle and State 5 of Virginia, have invented certain new and useful Improvements in Hammocks, of which the following is a specification.

This invention relates to hammocks and has special reference to that class of hammocks in which a canvas or other fabric body is suspended by means of ropes or other flexible attachments secured to the ends of the body, and in which a spreader bar is fitted in one end of the body so as to 10 extend the fabric at the head of the hammock.

15 The present invention has for its object the provision of simple and inexpensive means for securing the spreader bar within the fabric and also attaching the suspending cables or other devices to the hammock.

20 The invention also seeks to facilitate the removal of the fabric for washing, repairing or other purposes, as well as the attachment and adjustment of the cables or suspending devices.

25 The invention is illustrated in the accompanying drawings and will be hereinafter fully described, the novel features of the invention being subsequently particularly pointed out in the claim following the description.

30 In the drawings: Figure 1 is a plan view of a hammock embodying my present improvements; Fig. 2 is an enlarged detail section through the spreader bar and showing the manner of attaching the suspending cable thereto; Fig. 3 is a plan view of the same; and Fig. 4 is a plan view illustrating 35 a slight modification.

40 A hammock constructed in accordance with my invention is preferably composed of a body 1 of canvas or other fabric having its edges folded over upon its main portion and stitched thereto, as indicated at 45 2, to form hems 3. Through the hem at the head of the hammock, I insert a spreader bar 4 which is equal in length to the width of the fabric body, and the said spreader bar is provided with a plurality of eyes or 50 rings 5 to which the suspending cable 6 is attached. A similar construction is employed at the foot end of the hammock, but at this end the bar does not extend the 55 entire width of the hammock and, instead of a single bar, I preferably employ a plu-

rality of short bars or blocks, as indicated in Fig. 1 of the drawings. The eyes 5 are preferably screw eyes, the shanks of which are inserted through the hem of the fabric 60 so as to enter the bar through the edge of the same, as indicated clearly at 7 in Fig. 2. This construction is very cheap and, at the same time, possesses the necessary strength and provides means whereby the 65 fabric body may be securely attached to the bar at the same time the eyes or rings to receive the suspending cable are brought into position.

The suspending cable is attached to the 70 eye or ring preferably in the manner clearly shown in Figs. 2 and 3, upon reference to which it will be seen that the end of the cable is inserted through the eye, as indicated at 8, and is then carried around the 75 shank of the eye between the head or the body of the same and the hammock bar, as shown at 9, the extremity of the cable being then inserted through the uppermost bight 10 of the cable between the same and 80 the body or head of the securing ring or eye, as shown at 11. The extremity of the cable may then be knotted, as indicated at 12, if desired, to prevent raveling, or may be otherwise finished, as may be preferred. 85 It will be readily noted that, when the cable has been applied to the eye or ring, in the manner shown and described, which may be accomplished very quickly and easily, any strain exerted upon the suspended cable by 90 the weight placed upon the hammock, when the same is in use, will tend to draw the bight 10 of the cable more closely to and in more intimate contact with the portion of the cable passing therethrough, and will 95 bind or clamp said portion against the eye or ring so that the separation or withdrawal of the cable from the eye will not occur. The greater weight placed upon the hammock, the more securely will the cable be 100 clamped in the attaching eye or ring.

105 The provision of attaching eyes or rings beyond the ends of the fabric body permits the use of the particular knot or fastening shown and described in detail, and this knot is very desirable as it may be rapidly formed at any point along the cable and any desired length of cable attained between the fixed support and the hammock body. Moreover, the sustaining strain is not concentrated on 110 a few threads of the fabric but will be transmitted through the blocks and caused to di-

verge through a large number of strands and eventually spread over the entire area of the body through the stitching which secures the hem.

5 In Fig. 4, I have shown a slight modification of the invention, in which the attaching eye or ring, indicated at 13, is formed integral with the hammock bar 14, which may be of metal. In the use of this particular construction, the fabric for the hammock body will be provided with small slots which will be engaged over the attaching eye, whereas, in the previously described form, it is not necessary to provide such 15 slots in the fabric, as the openings will be formed by the insertion of the screw shanks therethrough.

Other modifications may be made without departing from the scope of the invention 20 as the same is defined in the following claim, and it will be readily noted that I have provided an exceedingly simple and inexpensive device, by the use of which the hammock body will be very firmly secured 25 to the hammock bar and suspended from its support. In both illustrated forms, it

will be noted that a space is provided between the hammock bar and the edge or side of the eye, ring, hook or loop in which the suspending cable may be frictionally 30 clamped. It will also be noted that the construction is such that the body fabric may be easily removed from the hammock bar when necessary and the assembling of the parts in a complete hammock is a very simple proceeding.

Having thus described my invention, what I claim as new is:—

The combination of a hammock body fabric having hems at its ends, a hammock bar 40 in the hem at one end of the body fabric and co-extensive therewith, a plurality of shorter bars in the hem at the opposite end of the fabric, attaching rings carried by the bars, and suspending cables secured to said 45 rings.

In testimony whereof I affix my signature in presence of two witnesses:

WILLIAM H. DAVIS. [L.S.]
